FOUNDATION GARMENT

Ethel Rorke Kaupp, Forest Hills, N. Y., assignor
to Vogue Mfg. Co., Newark, N. J., a corpora-
tion of New Jersey

Application April 8, 1938, Serial No. 200,858

6 Claims. (Cl. 2—30)

This invention relates to foundation garments for women's wear; and the invention has reference, more particularly, to an improved foundation garment comprising a girdle of novel construction capable of use with or without a brassière section, but constructed and arranged especially for cooperation with a novel brassière section adapted to be separably and interchangeably united therewith to form a novel composite or all-in-one foundation garment.

It is frequently the desire among women, and in fact it is the present trend of fashion, that the figure be molded to attain long waisted effects with high bust contours. It is an object of this invention to provide a novel construction of foundation garment which is calculated to mold the wearer's figure so as to attain such desiderata.

The invention has for a further object to provide a novel composite foundation garment comprising a girdle section having high cut sides and a novel breast lifting elastic panel at its central upper front portion, together with a novel shoulder strap means, each strap thereof having bifurcate front end portions, the arms of which connect respectively with the peak of said central panel and a side of said girdle section, and a novel brassière section, together with cooperative means for detachably connecting the front of the same to said shoulder strap means, and means for detachably connecting the back thereof to the girdle back, which is desirable in most cases, all so arranged and related as to attain a floating effect with respect to said brassière section which automatically allows the latter to adjust itself to the desired bust elevation.

Other objects of this invention, not at this time more particularly enumerated, will be understood from the following detailed description of the same.

An illustrative embodiment of this invention is shown in the accompanying drawing, in which:

Fig. 1 is a front face view or elevation of the novel foundation garment according to this invention; and Fig. 2 is a rear face view or elevation of the same.

Fig. 3 is an enlarged fragmentary vertical longitudinal sectional view of the garment.

Similar characters of reference are employed in the hereinabove described views, to indicate corresponding parts.

Referring to the drawing, the novel foundation garment comprises a lower garment section 5 in the form of a girdle and an upper garment section 6 in the form of a brassière.

The girdle section 5 comprises a body encircling structure adapted, preferably, to open in full or partially along a suitably located longitudinal line, the opening thus provided being provided with suitable means for closing the same, such, e. g., as the well known slide fastener means indicated by the reference character 7.

Said girdle section 5 comprises a lower front panel 8, preferably non-elastic, having, joined to its upper end portion, an upper front panel 9 made of elastic material capable of vertical or up and down stretch. Joined to the sides of said lower and upper front panels 8 and 9 are side panels 10, which are preferably made of elastic fabric capable of two way stretch, i. e., capable of stretching both perpendicularly and transversely. Joined to and extending between the rearward side margins of said side panels 10 is a back panel 11, which is preferably made of non-elastic fabric. Said back panel 11 is of less upwardly extending length than are said side panels 10. Connected with the upper end of said back panel 11 is a non-elastic center strip 12, and extending obliquely downward from the upper portions of said rearward side margins of the side panels 11, to converge upon said center strip 12, in secured relation to the sides of the latter, are obliquely stretchable elastic fabric inserts 13.

The upper end portions of said side panels are high cut, and extend, from the rear portions thereof, forwardly below the arm-pits of the wearer so as to terminate in end peaks 14, which are adapted to be disposed adjacent to and somewhat forward of the wearer's arm-pits. The elastic front panel 9 is provided with curved upper margins 15 which extend around and beneath the wearer's breasts, and thence in upwardly converging relation, thereby providing an upwardly directed central extension 16 which passes upwardly between the wearer's breasts.

Affixed to the upper marginal portions of the back of the girdle section are the rearward end portions of shoulder straps 17, said rearward end portions of said straps 17 preferably terminating in longitudinally stretchable elastic sections 18. Said straps 17 are provided at their forward portions, with adjustment loops 19 having controlling slide pieces 20, whereby the length of the straps may be suitably varied as required. Said adjustment loops 19 are coupled by connecting links 21 with front strap-end portions 22. Each front strap-end portion 22 terminates at its lower end in downwardly extending divergent branches or arms 23 and 24. The inner branches or arms 23 are secured to the upper extremity of the cen-

tral extension 16 of said elastic front panel 9, while the outer branches or arms 24 are secured respectively to the end peaks 14 of the respective side panels 10. The divergent branches or arms 23-24 are thus disposed to pass from points adjacent the sides of the wearer's breasts to converge upon the strap-end portions 22 at points above the wearer's breasts.

By the described novel construction of the 10 upper side and front portions of the girdle section as combined with the novel shoulder strap structure, an upward lifting embrace is independently afforded as to each breast, whereby the wearer's bust is brought into the desired high 15 position. Due to the up and down stretch of the upper front panel 9 and its extension 16 which lies between the breasts, not only is upward lift exerted upon the breasts, but also a desired lateral separation thereof is obtained which is calculated to produce an individual molding effect 20 thereupon with accompanying symmetrical lateral spacing whereby the pleasing lines and contours of high bust effect is assured. At the same time due to the directional control of the elasticity or stretch of the upper front panel 9 and 25 its extension 16 over the diaphragm greater bodily freedom and comfort is assured without loss of said desired high bust effect. The novel arrangement of shoulder strap connection at the front 30 portions of the girdle section, so distributes the supporting pull of the straps that tendency of the flesh to roll in the vicinity of the waist line and under the arms is largely avoided, while at the same time the novel method of support eliminates 35 any tendency of the top portions of the girdle section to roll down.

Provided for cooperation and combination with the novel girdle section is a separable strapless brassière section. This brassière section comprises a suitably constructed front part having full-fashioned breast receiving members 25, terminating at their upper ends in top peak portions 26 to which are secured upwardly directed elastic attachment loops 27. Extending from the 40 sides of said breast receiving members 25 are side panels 28, to the rearward side margins of which are joined longitudinally stretchable elastic fabric rear portions 29. These rear portions 29 are preferably of tapering cut. The meeting ends of 45 said rear portions 29 are equipped with any suitable means for separably connecting the same together. Secured to and dependent from the rear portion of said brassière section, adjacent to the centrally meeting ends of its rear portions 50 29 is a rear attachment strap 30, preferably made of elastic tape. Said attachment strap is provided at its free end with a fastener hook 31 for selective cooperation with vertically spaced eyelets 32, with which said center strip 12 of girdle 55 section is provided. The shoulder strap end portions 22 of the girdle section preferably extend slidably through the links 21 and are provided at their upper ends with suitable designed hook-plates 33 dependent therefrom. When the brassière 60 section is arranged in place, the elastic attachment loops 27 are engaged with the hook-plates 33, thus suspending the top peak portions 26 of the brassière breast receiving members 25 from the shoulder straps of the girdle section, and 65 thereby operatively associating the front portions of the girdle and brassière sections together. The back portions of the girdle and brassière sections are separably connected together by engaging the fastener hook 31 of the rear attachment strap 30 with a selected eyelet 32 of

the center strip 12 of the girdle section. The latter arrangement allows for vertical relative adjustment of the brassière and girdle sections. It will be obvious that by the described arrangement the brassière and girdle sections are operatively associated together to form an all-in-one or composite foundation garment, in which the one set of shoulder straps serves to support both sections of the garment, while at the same time this novel method attaching the brassière and girdle sections together permits of a somewhat floating association of the brassière section relative to the girdle section, and consequently permits the former to automatically adjust itself to the high bust disposition which the garment provides for. 10 15

It will be understood that many apparently widely different embodiments of this invention could be made without departing from the scope thereof as defined in the following claims; it is therefore intended that all matter contained in the above description or shown in the accompanying drawing shall be interpreted as illustrative and not in a limiting sense. 20

I claim:

1. In a foundation garment, a girdle section having high cut side portions, a perpendicularly stretchable panel at the upper front portion of said girdle section between said side portions thereof, said panel having concavely curved top marginal portions to extend around and beneath the breasts of the wearer, said panel having a central upwardly directed extension to extend between the wearer's breasts and upon which said curved top marginal portions converge, shoulder straps extending from the top rear margins of said girdle section, each shoulder strap terminating at its front portion in divergent branches connected respectively with the upper end of the extension of said upper front panel and with the top portion of an adjacent girdle side portion, a brassière section having breast receiving members, and cooperative means connected with the top margins of said receiving members and with said shoulder straps for separably connecting the former in suspended relation from the latter. 25 30 35

2. In a foundation garment, a girdle section having high cut side portions, a perpendicularly stretchable panel at the upper front portion of said girdle section between said side portions thereof, said panel having concavely curved top marginal portions to extend around and beneath the breasts of the wearer, said panel having a central upwardly directed extension to extend between the wearer's breasts and upon which said curved top marginal portions converge, shoulder straps extending from the top rear margins of said girdle section, each shoulder strap terminating at its front portion in divergent branches connected respectively with the upper end of the extension of said upper front panel and with the top portion of an adjacent girdle side portion, a brassière section having breast receiving members, cooperative means connected with the top margins of said receiving members and with said shoulder straps for separably connecting the former in suspended relation from the latter, and cooperative means to separably connect together the rear portions of said girdle and brassière sections. 40 45 50 55 60 65 70

3. In a foundation garment, a girdle section having high cut elastic side panels to extend below the arm-pits of the wearer and terminating at their forward upper portions in end peaks 75

for disposition adjacent to and forwardly of said arm-pits, a back structure connected between the rearward sides of said side panels, a lower non-elastic front panel connected between the forward sides of said side panels, an elastic upper front panel capable solely of perpendicular stretch connected with the upper end of said lower front panel and between the forward sides of said side panels, said upper front panel having concavely curved top marginal portions extending inwardly from the end peaks of said side panels and around and beneath the breasts of the wearer, said elastic upper front panel having a central upwardly directed free extension to extend between the wearer's breasts and upon which said curved top marginal portions converge to form the apex thereof, shoulder straps secured to and extending from the top rear margins of said back structure, and each shoulder strap terminating at its front portion in divergent branches, the inner branches converging upon and being affixed to the apex of said upper front panel extension, and the outer branches extending respectively to and being affixed to the end peaks of the respective elastic side panels.

4. In a foundation garment, a girdle section having high cut side panels to extend below the arm-pits of the wearer and terminating at their forward upper portions in end peaks for disposition adjacent to and forwardly of said arm-pits, a back structure connected between the rearward sides of said side panels, a lower front panel connected between the forward sides of said side panels, a perpendicularly stretchable upper front panel connected with the upper end of said lower front panel and between the forward sides of said side panels, said upper front panel having concavely curved top marginal portions extending inwardly from the end peaks of said side panels and around and beneath the breasts of the wearer, said upper front panel having a central upwardly directed extension to extend between the wearer's breasts and upon which said curved top marginal portions converge, shoulder straps secured to and extending from the top rear margins of said back structure, each shoulder strap terminating at its front portion in divergent branches connected respectively with the free end of the upper front panel extension and with the end peak of the adjacent side panel, a brassière section having breast receiving members, cooperative means connected with the intermediate portions of the margins of said receiving members and with said shoulder straps for separably connecting the former in floating suspended relation to the latter and over the upper portions of said girdle section, and unitable rear end portions extending from the sides of said breast receiving members.

5. In a foundation garment, a girdle section having high cut side panels to extend below the arm-pits of the wearer and terminating at their forward upper portions in end peaks for disposition adjacent to and forwardly of said arm-pits, a back structure connected between the rearward sides of said side panels, a lower front panel connected between the forward sides of said side panels, a perpendicularly stretchable upper front panel connected with the upper end of said lower front panel and between the forward sides of said side panels, said upper front panel having concavely curved top marginal portions extending inwardly from the end peaks of said side panels and around and beneath the breasts of the wearer, said upper front panel having a central upwardly directed extension to extend between the wearer's breasts and upon which said curved top marginal portions converge, shoulder straps secured to and extending from the top rear margins of said back structure, each shoulder strap terminating at its front portion in divergent branches connected respectively with the free end of the upper front panel extension and with the end peak of the adjacent side panel, a brassière section having breast receiving members, cooperative means connected with the intermediate portions of the top margins of said receiving members and with said shoulder straps for separably connecting the former in floating suspended relation to the latter and over the upper portions of said girdle section, and unitable rear end portions extending from the sides of said breast receiving members, and cooperative means for separably anchoring said unitable rear end portions of the brassière section to the back structure of said girdle section.

6. In a foundation garment, a girdle section having high cut side panels to extend below the arm-pits of the wearer and terminating at their forward upper portions in end peaks for disposition adjacent to and forwardly of said arm-pits, a back structure connected between the rearward sides of said side panels, a lower front panel connected between the forward sides of said side panels, a perpendicularly stretchable upper front panel connected with the upper end of said lower front panel and between the forward sides of said side panels, said upper front panel having concavely curved top marginal portions extending inwardly from the end peaks of said side panels and around and beneath the breasts of the wearer, said upper front panel having a central upwardly directed extension to extend between the wearer's breasts and upon which said curved top marginal portions converge, shoulder straps secured to and extending from the top rear margins of said back structure, each shoulder strap terminating at its front portion in divergent branches connected respectively with the free end of the upper front panel extension and with the end peak of the adjacent side panel, a brassière section having breast receiving members, cooperative means connected with the intermediate portions of the top margins of said receiving members and with said shoulder straps for separably connecting the former in floating suspended relation to the latter and over the upper portions of said girdle section, and unitable rear end portions extending from the sides of said breast receiving members, and cooperative means for separably anchoring said unitable rear end portions of the brassière section to the back structure of said girdle section, said latter means comprising an elastic strap means having a fastener thereon, and vertically spaced fastener elements mounted on said girdle back structure for selective cooperation with said strap fastener element.
